DESIGN FOR AN ELECTRIC LAMP

Robert A. Rogers, Philadelphia, Pa., assignor to
Turnsignal Corporation, Philadelphia, Pa., a
corporation of New Jersey

Application February 27, 1940, Serial No. 90,554

Term of patent 14 years

To all whom it may concern:

Be it known that I, Robert A. Rogers, a citizen of the United States, residing at Philadelphia, county of Philadelphia, State of Pennsylvania, have invented a new, original, and ornamental Design for Electric Lamps, of which the following is a specification, reference being had to the accompanying drawing, forming part thereof.

Fig. 1 represents a top plan view of an electric lamp showing my new design.

Fig. 2 represents a bottom plan view of the same.

Fig. 3 represents a front elevational view of the same. The back of the lamp is identical in appearance with the front as shown.

I claim:

The ornamental design for an electric lamp, as shown and described.

ROBERT A. ROGERS.
